CLAIM

We claim the ornamental design for a computer screen with animated graphical user interface, as shown and described.

DESCRIPTION

FIG. 1 is a front view of a computer screen with animated graphical user interface showing a first image in a sequence; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; FIG. 8 is a front view of an eighth image thereof; FIG. 9 is a front view of a ninth image thereof; FIG. 10 is a front view of a tenth image thereof; FIG. 11 is a front view of an eleventh image thereof; and, FIG. 12 is a front view of a twelfth image thereof.

The dashed broken line perimeter is included for the purpose of illustrating a computer screen and forms no part of the claimed design. The dashed and square -dotted broken line indicia is included for the purpose of illustrating an animated graphical user interface and forms no part of the claimed design.

The dashed hatching, dotted hatching, and tonal shading are included for the purpose of illustrating a contrast in appearance that forms a part of the claimed design.

(Continued)

The appearance of the image transitions sequentially between the images shown in FIGS. 1-12, The process or period in which an image transitions to another forms no part of the claimed design.

1 Claim, 12 Drawing Sheets
